(57) **CLAIM**

The ornamental design for a cart, as shown and described.

DESCRIPTION

FIG. 1 is a perspective view of a cart showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is another perspective view of FIG. 1 to show the state after putting away the awning;

FIG. 9 is another perspective view of FIG. 1 to show the state after extending the awning; and,

FIG. 10 is another perspective view of FIG. 1, and the seat with awning is rotated 180 degrees horizontally.

The broken lines illustrate portions of cart and form no part of the claimed design.
